UNITED STATES PATENT OFFICE.

STRAUD K. WOOD, OF HUTCHINSON, KANSAS.

CAR-IDENTIFYING MEANS.

Application filed June 15, 1926. Serial No. 116,168.

The invention is an improvement over the casing element and associated parts of my Patent #1,519,472.

The object of the invention is to produce a holder of such character that it efficiently protects and utilizes a car-identifying card as a seal so that the card cannot be removed without mutilation, or without injury to the holder, as mutilation of such cards, in many States, is the cause for arrest and investigation. A further object is to produce a holder of the type mentioned, which is of simple, strong, durable and attractive appearance.

With these objects in view the invention consists in certain novel and useful features of construction and organization of parts as hereinafter described and claimed; and in order that it may be readily understood, reference is to be had to the accompanying drawing, in which:

Fig. 1 is a front view of one embodiment of my invention.

Fig. 2 is a back view of Fig. 1.

Fig. 3 is a sectional elevation along the lines 3—3 of Fig. 1.

Fig. 4 is a sectional view along the line 4—4 of Fig. 1.

Fig. 5 is an enlarged detail of the mutilation means.

Fig. 6 is an enlarged view of a portion of Fig. 4.

In the said drawing the holder is shown as composed of two sheet steel or equivalent members of rectangular form, secured together and sealed in such relation by an identification card held between the members and readable but not accessible through a window in the front member.

The back member 1 is pressed out to provide a rectangular recess 2, and is turned or flanged back at its upper end at 3 to provide a downwardly-opening groove or channel. Within the recess, is a pair of resilient hooks 7, formed at opposite ends of a plate 8 secured to the back wall. The transparent plate is shown at 10 having depressions 11 moulded therein and adapted to receive the ends of the hooks 7 when pressure is brought to bear on the plate 10.

The front member 12 corresponds in size and form to member 1, but is flanged at its side margins at 13 to provide grooves for the reception of the side edges of the back member, and with an upturned flange 14 at its lower end, to produce a groove for the reception of the lower end of the back mem-

ber, the upper end of the front member being adapted to enter the groove 3 of the back member. To secure the members together as explained, they are arranged end to end and relatively slid longitudinally to cause the side edges of the back member to engage the side grooves of the front member, and when so related they are finally interlocked at all four edges and cannot be separated except by reversing the sliding movement.

The front member is formed with a recess 15, the plate being pressed outwardly so that when the front and back members are interlocked together as explained, a compartment for receiving the glass plate and certificate is formed. The front member is provided with a window opening 16 with bolt cut outs 17 to register with holes 5 in offset ears 6 in the back. The transparent plate 10 fits snugly in the recess 15, and a flexible identification card 20 is fitted over its inner face and interlocked with the plate 10 by being bent over the upper and lower ends of the latter as at 21, so that the card cannot slip or buckle between said plate and the back member.

On assembling the members in interlocked relation as explained the transparent plate with the card folded thereover is first placed in its recess in the front plate and the back plate 1 slid into position; the card during the sliding movement, represses the hooks 7 until a pair of perforations 22 in the certificate register with the lower ends of the hooks. As this occurs the sliding movement is completed and the hooks enter the said perforations 22 so that the card or certificate by engagement with the hooks, serves to make it impossible for the plates to again separate by reverse sliding movement, without tearing the card from said perforations upward. Nor can the window plate be broken and removed piecemeal to effect the removal of the card without injury to the latter. If the plate 10 is cut out at the margins of opening 16, the card cannot be removed intact, as there would still remain a frame of glass clamping the card at its margins against the plate of the other or back member. It will be apparent, therefore, that it would be impracticable for anyone to readily remove a card for the purpose of replacing it with a fraudulent one, and even if this was done, it would be instantly discovered when an attempt was made to secure a new license, as with this system it is

contemplated that the State authorities shall retain a duplicate of the required card and compare same with the original or a replacement thereof, before issuing a new license or 5 permit.

Nor can the glass 10 be pressed downwardly to bend back the hooks or mutilating members 7 and thus render them ineffective, as the depressions 11 moulded in 10 the glass 10 receives the ends of the mutilating members 7 without injury.

I also contemplate providing the cover or front plate with raised letters indicating the State issuing the same as shown at 25. In 15 like manner the same raised lettering appears on the glass 10. This is shown at 26. In order to further prevent substitution of an invalid certificate, I propose to sand blast the license number corresponding to the 20 certificate in the back side of the glass as at 27 and provide these same numbers in raised form on the cover plate as at 28.

The holder is adapted to be secured upon the instrument board or other suitable place 25 on a car. If upon the instrument board, securing bolts 23 are fitted through the registering holes 5 and cut outs 17 and nuts 24 or the like, are employed to clamp the two 30 members together and to the said instrument board.

If the law requires that the card contain printed matter on the back as well as on the front, the holder will preferably be secured adjacent the wind shield, so that the 35 card may be in convenient position for inspection at both sides.

The turned over flanges of both cover and back plates are provided with weakening indentations 29 so that if an attempt be made 40 to bend back these flanges to remove the certificate, the flanges will break off and the casing cannot be further used.

As after the device has been on a car for some time there is a tendency for the front 45 and back to stick together, I provide a tongue 30 in the back which projects through a slot 31 at the bottom of the cover. When, therefore, the casing is removed and the bolts 23 removed from the cut out portion of 50 the cover and ears of the back, the device may be brought down sharply on a hard sur-

face so as to strike the tongue 30, and the cover and back thus separate.

I claim:—

1. In a device of the character described, a 55 casing comprising two slidably-related members, one having a window opening, a transparent plate covering the opening, a certificate within the casing, and one or more mutilating members within the casing and 60 adapted to mutilate the certificate in the event the said members are slidably operated to give access to the interior of the casing, said transparent plate having a depression therein receiving one of the mutilating 65 members.

2. In a device of the character described, a 70 casing comprising two slidably-related members, one having a window opening, a transparent plate covering the opening, a certificate within the casing, and one or more mutilating members within the casing and 75 adapted to mutilate the certificate in the event the said members are slidably operated to give access to the interior of the casing, one of said slidably-related members having a portion projecting through the other member for forcibly separating the same.

3. In a device of the character described, a 80 casing comprising two members slidably interlocked together at opposite edges, one having a window opening, one or more mutilating members within the casing and fixed thereto as regards one of its said members 85 but capable of reposition toward the same, a transparent plate within the casing between said mutilating members and the said window opening and closing the latter to prevent access to the interior of the casing, 90 and a certificate within the casing between the said plate and mutilating members for mutilation by the latter in the event the members are slid to effect separating or disengaging movement, said interlocking portions of the casing having weakening indentations whereby the interlocked parts will 95 break off when bent.

In testimony whereof, I have affixed my signature.

STRAUD K. WOOD.
